YARN BEAMING MACHINE

Wilhelm Reiners and Gustav Kahlisch, Munchen-Gladbach, Germany, assignors to W. Schlafhorst & Co., Munchen-Gladbach, Germany, a corporation of Germany

Application April 19, 1932, Serial No. 606,240
In Germany July 2, 1931

14 Claims. (Cl. 28—32)

Our invention relates to a machine for beaming yarn in cross winding, for bleaching and dyeing and like purposes.

The wet treatment of yarn, that means bleaching, dyeing and the like, on the beam is already known for decades, but has gained extraordinarily in importance during the last years. The essence of this wet treatment consists in the yarn being wound on to a beam in a continuous course, quite like with the so-called warping frames used in weaving, the beam used, however, having the form of a perforated cylinder which after having been wrapped is inserted into the circulation of the liquor. The circulation is reversed from time to time, so that the liquor oozes through the yarn layers surrounding the beam alternatively from outside to inside and inversely. Now, in order to obtain a satisfactory and uniform dyeing effect it is necessary that the yarn in beaming is wound always with uniform tension and uniform density, in order that uniform resistance is offered throughout to the liquor oozing through the yarn layers. This winding has its difficulties and, therefore, no uniform dyeing effect is frequently obtained in the dyeing operation. This is of importance especially if several yarn beams have to be treated with one and the same liquor and, more particularly, in dyeing with bright colors. As the threads on the beam lie close together and close upon one another, the liquor has not the possibility to advance everywhere and uniformly up to the individual threads, this being the case especially with the threads situated at the ends of the beam. For, on running on to the beam, these threads are urged axially inwardly by the flanges of the beam and, therefore, frequently come to lie more closely on one another than the threads situated in the midst of the beam.

In order to overcome all the drawbacks mentioned, it has been suggested to wrap the yarn beams with cross winding, to obtain in this way a more porous yarn body or bobbin. With the machines proposed for this cross winding, however, the stationary axially moving comb p , as illustrated in the schematic Figure 1, is situated far away from the place where the threads run on to the beam. The consequence thereof is, that the stroke of the guide comb at that place results in a nearly parallel position of the threads and no marked crossing, and thus no sufficient porosity enabling an easy and uniform passage of the liquor is obtained. Furthermore, with cone warping frames it has been suggested to dispose the guide comb as near as possible to the place

where the yarn runs on to the beam. However, also in this case, the place where the thread leaves the guide comb is not situated immediately in front of the place where the thread runs on to the beam, but so far away therefrom, that a satisfactory crossing of the threads is impossible. Cylindrical yarn bobbins as they are obtained by means of the machine according to the present invention, therefore cannot be produced by means of this known appliance. Furthermore, warps wound on cone warping frames cannot be used at all on the beams of these machines for the wet treatment, such as bleaching, dyeing or the like, but have to be unwound on suitable special machinery and re-wound on to special dyeing beams. The object of our present invention is to remedy these drawbacks.

In the machine forming the subject-matter of the invention the guide comb, formed by a plurality of teeth which are rigidly disposed at least in the direction of reciprocating movement of the comb, is disposed in close proximity to the place where the threads run on to the beam, as illustrated in the schematic Figure 2. The threads thus always run from the guide comb directly on to the beam or the windings already existing thereon. The crossing of the threads caused by the axial reciprocating motion of the guide comb or beam thus has a full effect upon the threads running on to the beam. In connection with such a supply of the threads, a beam fitted at its ends with flanges cannot be made use of, indeed, as the flanges would laterally interfere with the course of the thread. Therefore such beams have to be employed, the flanges of which are removable, or at least adapted to be displaced axially so far away from the ends of the yarn bobbin, that no interference with the course of the thread occurs. Furthermore, as the diameter of the bobbin permanently increases during the winding operation, the guide comb has to recede progressively from the beam in accordance with the gradually increasing diameter of the bobbin, in order to obtain the object aimed at, namely the running of the thread from the guide comb directly on to the beam. This may be achieved in different ways: The guide comb or its carrier which advantageously is designed as a travelling roller, is either mounted on weight-loaded swing levers in such a manner that it adjusts itself quite automatically according to the altering diameter of the beam, or the guide comb or its carrier is displaced mechanically according to this alteration. Finally, the guide comb may be disposed stationary, whilst the beam is mounted movably, for

instance on swing levers balanced by counter-weights which are displaced automatically according to the increasing weight of the beam, the latter with the bobbin thereon abutting 5 against the guide comb and being pressed away by the latter with increasing bobbin diameter. A mechanical adjustment of the guide comb or beam affords the advantage that the guide comb or its carrier is not in contact with the yarn 10 on the beam. For, there are certain coloring matters and artificial silks which do not permit such a contact due to the friction of the yarn resulting therefrom. At all events, however, in order to achieve the object aimed at, namely a 15 satisfactory crossing of the threads even with a mechanically displaced guide comb or beam, the guide comb must always remain within the angular space that comes into question for the bobbin to be wound, as marked by the dotted lines 20 in Figures 2 to 4 and 5 to 10.

Fig. 1 shows the association of a guide comb with a yarn beam according to the prior art,

Fig. 2 shows the cooperation of a guide comb with a yarn beam according to the instant invention,

The Figures 3 to 10 show several embodiments of the yarn beaming machine forming the subject-matter of our present invention.

Fig. 1 shows diagrammatically a yarn beam 30 empty and in various stages of being loaded with yarn and an axially movable guide comb, *p* at a usual distance from the body of the beam.

Fig. 2 shows a yarn beam 2 empty and in various stages of being loaded with yarn and an 35 axially movable guide comb 3 controlling a group or groups of threads arranged tape-fashion side by side in a sheet. The threads bodily traverse the beam by means of the reciprocating guide comb 3, which is always kept in close proximity 40 to the winding-on points on the beam in such a fashion that in the traversing operation, the threads of the group or of each group overlap each other in a way insuring a certain control of the mesh formation to a degree allowing an easy 45 penetration of the liquor.

In the machine illustrated in Figures 3 and 4 the threads 1 coming from the creel run through the guide comb 3 to the perforated beam roller 2 which is mounted on a shaft 14 and receives 50 rotary motion from a belt gear by means of an intermediate spur wheel gear train 12, 13. The guide comb 3 is carried by a rail 4 and receives its axial reciprocating motion by means of a cam disc 5, the shaft of which is mounted on swing 55 levers 6, 7, which further carry the guide comb 3, rotary motion being imparted to disc 5 by a chain drive 8, 9, 10. With increasing beam diameter, the guide comb 3 which rests on the bobbin, or the carrier 4 with the guide comb rises by virtue of its mounting on the weight-loaded swing 60 levers 6. This change of position results in an alteration of the pressure exerted by the carrier upon the bobbin and, as a consequence thereof, the yarn would be wound under different load, 65 that means, with different density. In order to overcome this drawback, the weights 11 mounted on the swing levers 6, 7 are displacable. In order, further, to prevent jumping of the guide comb 3 by the yarn running to the beam, the weight-loaded arms of the swing levers 6, 7, are guided 70 between adjustable braking jaws 15.

Inversely, as schematically illustrated in Figure 5, the guide comb 3 may be mounted fixedly, while the beam 2 is movable and abuts with the windings thereon against the carrier 4 of the guide

comb and is pressed down by the latter with increasing beam diameter. In accordance with the increasing diameter or weight of the beam, the counter-weights are automatically displaced along the rear arms of the swing levers 28 by means of rods 29 which are fulcrumed at 30 and linked at 31 to the weights 11.

If the guide comb has a uniform pitch on the entire width of the beam, as illustrated in Figure 6, the two front ends of the bobbin become rather 10 inclined due to the strong crossing of the threads. This results in the fact that the marginal threads become shorter than the remaining ones and break when unwound, due to their greater tension. In order to avoid this disadvantage, according to the invention the dents and corresponding 15 teeth of the guide comb that are adjacent the two ends of the beam increase towards these ends gradually and uniformly. In this way so much 20 more yarn is wound on these places, that the bobbin becomes cylindrical up to its both ends or tapers there only to a negligible extent.

The embodiment illustrated in Figure 7 of the machine forming the subject-matter of the invention differs from the embodiments hereinbefore described by the design of the guide comb 3. In this case, the guide comb 3 is not constructed as a single bar with the guide dents disposed in a straight line, but as is the case with the showing in Fig. 4, the same is composed of a 30 plurality of sections spacedly fixed in straight or inclined position on a common axially reciprocating carrier, (Figure 7). Each separator section serves to feed to the beam a group of threads. This peculiar feed of the threads in the form of 35 ribbons results in the formation of disc-shaped cylindrical cross wound yarn bodies, as will be seen from Figure 7, which bodies according to the invention together form a complete warp beam. In this way the advantage is achieved for colored 40 weaving, where the warps contain very many differently colored threads and very many narrow warps are employed, that individual cross wound disc-shaped bobbins may be withdrawn from beams formed in this way and dyed, which bobbins then may be composed again so as to form 45 a new multi-colored beam. According to the number of the threads to be wound and to the number of threads united in such a ribbon, the number of the bobbins to be formed varies, it is 50 not subject to any limitation and the number may decrease to a single bobbin. In this latter case only one sole undivided cylindrical cross wound warp bobbin is formed on the beam.

It may be stated that subdivided guide combs 55 are already known in warping frames, but here they are expansion guide combs which do not admit formation of disc-shaped bobbins. For the production of the latter the guide comb sections must not form the continuation of one another, 60 but have to be arranged spacedly from one another at a distance equal to the stroke of the reciprocating guide comb.

Furthermore, also the manufacture of cross wound yarn bodies on warping frames by means 65 of ribbons composed of individual threads is already known, and also the simultaneous production of a series of juxtaposed cylindrical cross wound bobbins by means of ribbon-like thread groups.

The embodiment of the invention illustrated in Figures 8 and 9 differs from the embodiments hereinbefore described by the fact that the guide comb 3 with its carrier does not rest on the bobbin or bobbins, but is positively held, even with in-

creasing diameter of the latter, at a slight distance therefrom. In the embodiment illustrated this positive distant adjustment of the guide comb is established in the following manner: The swing 5 levers 6 and 7 which carry the guide comb 3 have pivotally mounted on them screw nuts 16 through which pass screw spindles 17. The latter rest in footstep bearings 18 likewise pivotally mounted on the machine frame. The lower ends of the 10 spindles 17 project beyond these bearings 18 and there each carries a bevel wheel 19 which is in mesh with a companion wheel 20 rigid to a shaft 21. The latter is mounted in the machine frame and outside the frame carries a ratchet 15 wheel 22 which is turned from a crank disc 25, through the intermediary of transmission levers 23, 24, by a pawl 26 by the angular amount of two or more teeth in each revolution of the crank disc 25. By this motion, through the intermediary 20 of the bevel gear 19, 20, also the spindles 17 are turned correspondingly, whereby the swing levers 6, 7 with the guide comb 3 carried by them are lifted. This movement may be varied by a greater or lesser swinging angular movement 25 according to the thickness of the yarn and corresponding to the amount of increase of the diameter of the beam. When the beam is completely wrapped, the guide comb 3 can again be lowered to its initial position relatively to a new 30 blank beam by turning a hand wheel 26a, Figure 9.

In the embodiment illustrated in Figure 10, the guide comb, in contrast to the arrangement shown in Figures 8 and 9, is not swingingly mounted 35 but is rigid, as in Figure 5, while the beam is mounted for positive motion on swing levers 27, in order to obtain the desired permanent equal distance of the guide comb from the periphery of the bobbin or bobbins on the beam. The positive motion of the swing levers 27 is produced 40 by the same means as is shown in the embodiment of Figures 8 and 9.

Also, in the embodiments illustrated in the Figures 8 to 10 of the machine forming the subject-matter of the present invention, the winding 45 of the beam may be carried out either by winding thereon one continuous bobbin or a plurality of bobbins from ribbon-like united yarn groups, as in the embodiments shown in Figures 7 and 9.

50 What we claim and desire to secure by Letters Patent is:—

1. In a machine for beaming yarn in substantially cylindrical cross-wound forms composed of a plurality of threads, a winding beam, means for 55 rotating said beam, a rectilinear guide comb having a plurality of rigidly disposed teeth therein for separating and guiding said plurality of threads and disposed closely adjacent said beam, means for reciprocating said guide comb longitudinally of said beam, and means for mounting said beam and guide comb to render them relatively movable in a transverse direction to permit said adjacent relationship between said comb and beam to be maintained throughout the winding 60 operation in order to obtain a substantially uniform mesh formation of the yarn.

2. In a machine for beaming yarn in substantially cylindrical cross-wound forms composed of a plurality of threads, a winding beam, means for 65 rotating said beam, a rectilinear guide comb having a plurality of rigidly disposed teeth therein for separating and guiding said plurality of threads and disposed closely adjacent said beam, means for reciprocating said guide comb longitudinally of said beam, and means whereby the

relative placement of said guide comb and said beam is varied in accordance with the increased diameter of said wound beam whereby said adjacent relationship between said guide comb and beam is maintained throughout the winding operation in order to obtain a substantially uniform mesh formation of the yarn. 5

3. In a machine for beaming yarn in substantially cylindrical cross-wound forms composed of a plurality of threads, a winding beam, means for 10 rotating said beam, a rectilinear guide comb having a plurality of rigidly disposed teeth therein for separating and guiding said plurality of threads and disposed closely adjacent said beam, supporting means for said guide comb, means for reciprocating said guide comb longitudinally of said beam, and means whereby said supporting means and said guide comb are withdrawn from said beam as the diameter of the wound beam increases whereby said adjacent relationship between said guide comb and beam is maintained throughout the winding operation in order to obtain a substantially uniform mesh formation of the yarn. 15

4. In a machine for beaming yarn in substantially cylindrical cross-wound forms composed of a plurality of threads, a winding beam, means for 20 rotating said beam, an axially moving guide comb for the several yarn threads closely adjacent said beam, supporting means for said guide comb comprising a rockable frame, a rotatable cam mounted in said frame in cooperation with said guide comb for reciprocating the latter, and means whereby said rockable frame and said guide comb are withdrawn from said beam as 25 the diameter of the beam increases, whereby said adjacent relationship between said comb and beam is maintained throughout the winding operation in order to obtain a substantially uniform mesh formation of the yarn. 30

5. In a machine for beaming yarn in substantially cylindrical cross-wound forms composed of a plurality of threads, a winding beam, means for 35 rotating said beam, a rectilinear guide comb having a plurality of rigidly disposed teeth therein for separating and guiding said plurality of threads and disposed closely adjacent said beam in contacting relation with the windings thereon, means for reciprocating said guide comb, said beam and guide comb being relatively movable 40 whereby the increasing diameter of said wound beam automatically causes a relative displacement between said comb and beam while maintaining said contacting relationship throughout the winding operation in order to obtain a substantially uniform mesh formation of the yarn. 50

6. In a machine for beaming yarn in substantially cylindrical cross-wound forms composed of a plurality of threads, a winding beam, means for 55 rotating said beam, an axially moving guide comb for the several yarn threads closely adjacent said beam and slightly displaced from the yarn winding thereon, means for reciprocating said guide comb, and means for positively controlling by the machine drive the relative placement of said guide comb and said beam to maintain the slight gap between the guide comb and the yarn winding constant for increasing diameters of said wound beam throughout the winding operation in order to obtain a substantially uniform mesh formation 60 of the yarn. 65

7. In a machine for beaming yarn in a plurality of commonly mounted, substantially cylindrical cross-wound forms each composed of a plurality of threads, a winding beam, means for rotating 70

- said beam, a rectilinear guide comb having a plurality of groups of rigidly disposed teeth therein, each of said groups of teeth adapted to separate and guide a group of threads disposed band-like side by side, to form a series of coaxial cross-wound bobbins, said guide comb being mounted closely adjacent said beam with the windings thereon, said beam and guide comb furthermore being relatively movable to permit said adjacent relationship between said comb and beam to be maintained throughout the winding operation in order to obtain a substantially uniform mesh formation of the yarn.
8. In a machine for beaming yarn, preparatory to processing treatments, in substantially cylindrical cross-wound forms composed of a plurality of threads, a winding beam, means for rotating said beam, a rectilinear guide comb having a plurality of rigidly disposed teeth therein for separating and guiding said plurality of threads and disposed closely adjacent said beam for substantially the complete length thereof, means for reciprocating said guide comb longitudinally of said beam, and means for mounting said beam and guide comb to render them relatively movable in a transverse direction for an extent controllable by the winding operation to permit said adjacent relationship between said comb and beam to be maintained throughout the winding operation in order to obtain a substantially uniform mesh formation of the yarn.
9. In a machine for beaming yarn, preparatory to processing treatments, in substantially cylindrical cross-wound forms composed of a plurality of threads, a winding beam, means for rotating said beam, a rectilinear guide comb having a plurality of rigidly disposed teeth therein for separating and guiding said plurality of threads and disposed closely adjacent said beam for substantially the complete length thereof, means for reciprocating said guide comb longitudinally of said beam, and means for mounting said beam and guide comb to render them relatively movable in a transverse direction controllable by the winding operation, as the diameter of the wound beam increases, whereby said adjacent relationship between said guide comb and beam is maintained throughout the winding operation in order to obtain a substantially uniform mesh formation of the yarn.
10. In a machine for beaming yarn, preparatory to processing treatments, in substantially cylindrical cross-wound forms composed of a plurality of threads, a winding beam, means for rotating said beam, a rectilinear guide comb having a plurality of rigidly disposed teeth therein for separating and guiding said plurality of threads and disposed closely adjacent said beam for substantially the complete length thereof, supporting means for said guide comb, means for reciprocating said guide comb longitudinally of said beam, means for mounting said supporting means and said guide comb to render them relatively movable in a transverse direction controllable by the winding operation said mounting means being so disposed to withdraw said guide comb from said beam as the diameter of the wound beam increases whereby said adjacent relationship between said guide comb and beam is maintained throughout the winding operation in order to obtain a substantially uniform mesh formation of the yarn.
11. In a machine for beaming yarn, preparatory to processing treatments, in substantially cylindrical cross-wound forms composed of a plurality of threads, a winding beam, means for rotating said beam, an axially moving guide comb for the several yarn threads closely adjacent said beam for substantially the complete length thereof, supporting means for said guide comb comprising a rockable frame, a rotatable cam mounted in said frame in cooperation with said guide comb for reciprocating the latter, and means for mounting said supporting means and said guide comb to render them relatively movable in a transverse direction controllable by the winding operation for withdrawing said guide comb from said beam whereby said adjacent relationship between said comb and beam is maintained throughout the winding operation in order to obtain a substantially uniform mesh formation of the yarn.
12. In a machine for beaming yarn, preparatory to processing treatments, in substantially cylindrical cross-wound forms composed of a plurality of threads, a winding beam, means for rotating said beam, a rectilinear guide comb having a plurality of rigidly disposed teeth therein for separating and guiding said plurality of threads and disposed closely adjacent said beam in contacting relation with the windings thereon for substantially the complete length thereof, means for reciprocating said guide comb longitudinally of said beam, means for mounting said beam and guide comb to render them relatively movable in a transverse direction whereby the increasing diameter of said wound beam automatically causes a relative displacement between said comb and beam while maintaining said contacting relationship throughout the winding operation in order to obtain a substantially uniform mesh formation of the yarn.
13. In a machine for beaming yarn, preparatory to processing treatments, in a plurality of commonly mounted, substantially cylindrical cross-wound forms each composed of a plurality of threads, a winding beam, means for rotating said beam a rectilinear guide comb having a plurality of groups of rigidly disposed teeth therein, each of said groups of teeth adapted to separate and guide a group of threads disposed band-like side by side, to form a series of coaxial cross-wound bobbins, said guide comb being mounted closely adjacent said beam with the windings thereon, and means for mounting said beam and guide comb to render them relatively movable and controllable by the winding operation to permit said adjacent relationship between said comb and beam to be maintained throughout the winding operation in order to obtain a substantially uniform mesh formation of the yarn.
14. In a machine for bearing yarn in substantially cylindrical cross-wound forms composed of a plurality of threads, a winding beam, means for rotating said beam, and an axially moving guide comb for the several yarn threads closely adjacent said beam, means for mounting said beam and guide comb to render them relatively movable in a transverse direction to permit said adjacent relationship between said comb and beam to be maintained throughout the winding operation in order to obtain a substantially uniform mesh formation of the yarn, said guide comb having a plurality of teeth evenly spaced for the major portion of its extent and at the ends of said comb, for approximately the extent of the axial movement thereof, the teeth gradually increase in density towards the ends.
